UNITED STATES PATENT OFFICE.

THOMAS J. STAFFORD, OF AUDUBON, IOWA.

VENTILATOR ATTACHMENT FOR STOVEPIPES.

SPECIFICATION forming part of Letters Patent No. 770,329, dated September 20, 1904.

Application filed March 14, 1904. Serial No. 198,115. (No model.)

To all whom it may concern:

Be it known that I, THOMAS J. STAFFORD, a citizen of the United States, residing at Audubon, in the county of Audubon and State of Iowa, have invented a new and useful Ventilator Attachment for Stovepipes, of which the following is a specification.

My object is to restrict the escape of valuable products of combustion through a stovepipe as required to economize the burning of fuel, to draw cold and foul air from a room, to produce circulation of air in a room, to maintain a uniform temperature in a room, and to prevent the annoyances incident to the wind blowing down a chimney and forcing smoke, gas, and soot out of a stove.

My invention consists in the construction, arrangement, and combination of an air-circulating attachment to a stovepipe, as herein-after set forth, pointed out in my claim, and illustrated in the accompanying drawings, in which—

Figure 1 is a side view of a common stove and my attachment applied to the stovepipe as required in practical use. Fig. 2 is an enlarged sectional view of the device and shows how it is constructed and connected with a stovepipe.

The numeral 10 designates a stove, and 12 a pipe extending upward therefrom to be connected with a chimney.

My attachment consists of a pipe 13, half as large in diameter as the stovepipe and provided with a funnel-shaped lower end 14. It has a detachable elbow 15 at its top provided with a branch 17 at its bottom and center and a fixed pipe 16 near its top provided with a branch 17 to engage the branch extending down from the elbow 15. The elbow 15 and the pipe 16 are detachably connected with the stovepipe 12 by means of bushings α , fitted in apertures in the pipe 12, as shown in Fig. 2.

A damper 18 is located in the upper end portion of the pipe 13 as required to regulate the passage of cold and foul air upward through the ventilating-pipe.

In practical use when the damper in the pipe 13 is open cold and foul air will be drawn from the lower strata of air in the room and passed through the elbow 15 into the stovepipe 13 and in so doing will restrict the passage of heat from the stove up through the stovepipe 13, and consequently the heat will be retained and radiated from the stove and the lower portion of the stove as required to warm the atmosphere in the room, and heat in the branch pipe 16 will facilitate the movement of cold and foul air upward and out through the pipes 13 and 12. At the same time the heat distributed from the stove will be circulated in the room by the removal of the cold and foul air from the room through the pipe 13 as required to create a uniform temperature throughout the room.

It is obvious the passage of air through the pipe 13 may be regulated by means of the damper 18 or closed entirely as required to start a fire in the stove.

Having thus set forth the purpose of my invention, its construction, application, and manner of use, the practical operation and utility thereof will be readily understood by persons familiar with the art to which it pertains, and

What I claim as new, and desire to secure by Letters Patent, is—

A ventilator attachment for stovepipes comprising an open-ended pipe, about half the diameter of the stovepipe, provided with a damper and having a branch extending at right angles near its top and an upward extension on said branch, an elbow on the top of the pipe provided with a downward extension to connect with the upward extension of the said branch and flanged bushings in apertures in the stovepipe, arranged and combined to operate in the manner set forth for the purposes stated.

THOMAS J. STAFFORD.
